CLAIM

We claim the ornamental design for a batting helmet, as shown and described.

DESCRIPTION

FIG. 1 is a front perspective view of a batting helmet showing our new design;

FIG. 2 is a side view thereof;

FIG. 3 is a top view thereof; and,

FIG. 4 is a front view thereof.

The ornamental design that is claimed is shown in solid lines in the drawings. The broken (dashed) lines shown in FIGS. 1 through 4 are included only for the purpose of illustrating environmental elements, and form no part of the claimed design.
